CHILD'S SAFETY SEAT FOR A BARBER'S CHAIR

Thomas J. Collier, 109 N. Hanson St., Easton, Md.

Filed Apr. 13, 1965, Ser. No. 84,756

Term of patent 14 years

(Cl. D15—1)

FIG. 1

FIG. 2

FIG. 3

FIG. 4

FIG. 5

FIGURE 1 is a perspective view showing a child's safety seat for a barber's chair embodying my new design;

FIGURE 2 is a front elevational view of the seat;

FIGURE 3 is a top plan view of the seat;

FIGURE 4 is a bottom plan view of the seat; and

FIGURE 5 is an end view of the seat.

I claim:

The ornamental design for a child's safety seat for a barber's chair, as shown.
